DESIGN FOR A COMBINED CONTAINER AND LOLLIPOP DISPLAY

Arthur W. Lovejoy, Lowell, Mass., assignor to
C. A. Briggs Company, Cambridge, Mass., a corporation of Maine

Application May 26, 1942, Serial No. 107,015

Term of patent 14 years

To all whom it may concern:

Be it known that I, Arthur W. Lovejoy, a citizen of the United States, residing at Lowell, in the county of Middlesex and State of Massachusetts, have invented a new, original, and ornamental Design for a Combined Container and Lollipop Display, of which the following is a specification, reference being had to the accompanying drawing, forming a part thereof, and in which:

Fig. 1 is a front perspective view of a combined container and lollipop display, showing my new design; and

Fig. 2 is a side elevational view thereof.

I claim:

The ornamental design for a combined container and lollipop display, substantially as shown.

ARTHUR W. LOVEJOY.
